(57) **CLAIM**

The ornamental design for a set top box front panel, as shown and described.

DESCRIPTION

FIG. 1 is a right front perspective view of a set top box front panel showing our new design, the dotted portion is for reference only and does not form a part of our design; FIG. 2 is a top plan view thereof;

FIG. 3 is a bottom plan view thereof;

FIG. 4 is right end plan view thereof; and,

FIG. 5 is a left end plan view thereof.

The back side not shown does not form a part of our design.
